POUNCING MACHINE WITH HEATED
GREASE PADFrederick J. Berger, Danbury, Conn., assignor to
Doran Brothers, Incorporated, Danbury, Conn.

Application April 3, 1950, Serial No. 153,564

7 Claims. (Cl. 223—20)

1

This invention relates to a heated grease pad and more particularly to a heated grease pad for use on a machine in which the grease pad is reciprocated with respect to the hat body as it is moved across the surface thereof.

One of the objects of this invention is to provide a heated grease pad which is simple, practical, and thoroughly durable. Another object is to provide a heated grease pad which applies sufficient grease to even and darken the shade of a hat and properly retain the powder after it is used. Another object is to provide a heated grease pad of the above character which will secure a deeper penetration of the grease into the hat than is obtained by cold grease processing. Another object is to provide a heated grease pad of the above character which applies grease evenly over the entire surface being greased under conditions which insure adequate penetration of the surface being greased. Another object is to provide a heated grease pad of the above character which obtains the above objects by mechanical means rather than by hand as is now done. Another object is to provide mechanism of the above character which will be inexpensive to construct, operate, and maintain. Another object is to provide a pad of the above character which does not require the services of skilled labor. Another object is to provide a construction of the above character in which the electrical connections to the pad are efficiently and practically maintained despite the rotating and reciprocating movement of the pad. Other objects will be in part obvious and in part pointed out hereinafter.

In the accompanying drawings, in which is shown one of the various possible embodiments of this invention,

Figure 1 is a side elevation of a machine having the heated grease pad mounted thereon, certain parts of the machine being diagrammatically shown;

Figure 2 is a side elevation on an enlarged scale of the heated grease pad and mechanism associated therewith shown in Figure 1;

Figure 3 is a staggered vertical section taken substantially on the line 3—3 of Figure 2;

Figure 4 is a vertical section taken on the line 4—4 of Figure 3;

Figure 5 is a horizontal section taken on the line 5—5 of Figure 2;

Figure 6 is an exploded perspective view of certain elements in the body of the heating pad; and

Figure 7 is a vertical section taken through the grease pad assembly column.

Similar reference characters refer to similar parts throughout the several views of the drawings.

As conducive to a clearer understanding of certain features of this invention, it might here be pointed out that at the present time the greasing of crowns of hats is usually performed in either

of two ways. The first is to apply the grease by hand, using a grease pad heated on a lure stove, either as a complete operation, or as a touch-up after cold greasing on the machine. Hand greasing is a highly skilled operation, as either too much or too little grease will spoil the shade of the hat, an uneven application will cause streaks. The second is to use an unheated grease pad mounted upon a machine which moves the grease rag across the surface of a hat crown as the hat rotates. This method results in even application of the grease to the hat crown but the cold grease does not penetrate the felt sufficiently. Accordingly, it is another object of this invention to provide a practical and efficient heated grease pad for use on a machine which will apply grease evenly under conditions which will insure adequate penetration.

The heated grease pad assembly, generally indicated at 10 (Figure 1), is used on a machine of the type shown in U. S. Patent No. 2,137,250, in which the pad reciprocates vertically while in contact with a hat body.

In general, the heated grease pad assembly 10 includes a frame, generally indicated at 12 (Figure 4), which is mounted upon the upper end of a rod 14. During operation of the machine, the shaft 14 is reciprocated vertically, moving frame 12, and thus pad assembly 10, with a vertical reciprocating movement with respect to grease pad assembly column 16 (Figure 1). The pad, generally indicated at 18 (Figure 4), includes a pair of heating elements 20 and 22 (Figures 3 and 6), which heat pad 18 and thus the grease on a grease cloth 24 (Figure 4) fed across its face. The temperature of heating elements 20 and 22 is controlled by a variable voltage transformer (not shown). Conductors 26 and 28 (Figures 2 and 3) connect the heating elements 20 and 22 to contact members 30 and 32 mounted on a support 34 connected to and extending downwardly from the lower end of frame 12. The contact members 30 and 32 are engaged by a pair of carbon brushes 36 and 38, which are mounted in brush holders 40 and 42. Brush holders 40 and 42 are mounted upon a portion of assembly 16 (Figure 7) which is not reciprocated vertically, and brushes 36 and 38 (Figure 2) are connected to conductors 44 and 46, which are connected to a suitable source of current (not shown). Thus, when pad assembly 10 is reciprocated vertically, support 34 moves upwardly and downwardly between brushes 36 and 38 but contact members 30 and 32 are always in engagement with brushes 36 and 38, and thus maintain the circuit to heating elements 20 and 22.

In general, the machine upon which the heated grease pad assembly is shown includes a base 48 (Figure 1) having a column 50 mounted thereon. A shaft 52 is horizontally mounted on column 50 and is driven by a motor 55 through clutch 49, pulley 51, belt 54 and pulley 53. A chuck, gen-

erally indicated at 56, is mounted on the right-hand end of shaft 52 and is used for mounting hat blocks, such as block 57, supporting hat 58 on the machine. Pad assembly column 16 is pivotally mounted by a pivot pin 60 on a support 62 connected to base 48, and during operation of the machine, hydraulic mechanism (not shown) is provided for moving pad assembly column 16 about pin 60 so that pad assembly 10 moves over the crown so that during the operation the pad contacts the entire surface of the crown.

For reciprocating pad assembly 10, column 16 has a motor 64 mounted thereon, which drives a crank 66 (Figure 7). Crank 66 acts through connecting rod 68 and wrist pin 70 to drive rod 72 with a reciprocating action vertically with respect to column 16 whenever the machine is in operation. The lower end of rod 14 (Figure 4) threads into the upper end of rod 72 (Figure 7) and thus is driven by it.

Referring to Figure 4, pad assembly frame 12 includes portions 12a and 12b on which the outer raceways of bearings 76 and 78 are mounted. The outer raceway of bearing 76 is clamped against a seat 14a formed in the upper end of pad frame 12 by nuts 80. Bearings 76 and 78 pivotally mount frame 12 upon rod 14 so that pad assembly 10 may swivel with respect to rod 14 to maintain the surface of pad 18 tangent at all times to the surface being greased.

To permit brush holders 40 and 42 (Figure 2) to swivel with the pad assembly 10 during a greasing operation, they are mounted on a sleeve 82, which is rotatably mounted on column 16 (Figure 7) by means of bearings 84 and 86. To maintain sleeve 82 aligned with respect to pad assembly 10 during pouncing, pad assembly frame 12 is provided with a guide portion 12c. During operation of the pad assembly, guide portion 12c remains in engagement with an impregnated bronze guide block 85 secured to sleeve 82. Thus, as the pad assembly turns, its guide portion 12c acts through block 85 to turn sleeve 82 with it, keeping support 34 (Figure 2) centrally positioned between brush holders 40 and 42.

As is best shown in Figures 4 and 6, pad 18 is mounted upon frame 12 by screws 88. The inner portion of the pad is mounted within a recess 12d (Figure 6) in the face of frame 12 and includes a sheet of asbestos 90, a pair of sheets of mica 92, the heating elements 20 and 22, a pair of mica sheets 94, and a resilient element comprising a sponge rubber center 96 (Figure 4) having a vulcanized rubber surface 98 and a canvas backing 100. Screws 88 secure all of the elements of pad 18 in assembled relationship to frame 12, the heating elements being positioned within recess 12d. Preferably, a pair of metal clamping strips 102 and 104 are positioned between the heads of screws 88 and the rubber surface 98 to insure even clamping of the pad elements to the frame 12. This pad heats grease cloth 24 as it passes over its surface during a pouncing operation.

The grease cloth is in the form of a narrow strip of greased cloth which is fed from a roll positioned in a holder 108 (Figure 7) secured to the machine. The grease cloth passes upwardly over an idler roller 110, behind another idler roller 112 (Figure 4), and upwardly in a channel 114a formed in a guide plate 114. The cloth then passes over the top end of assembly 10 in contact with a curved guide strip 116, downwardly across the face of pad 18, to feeding gears 118 and 120. To maintain tension upon cloth 24 so that it will

remain in contact with the face of pad 18, a friction roller 122 is provided. Friction roller 122 is mounted on a frame 124, which is pivotally mounted by a pin 126 on frame 12. A leaf spring 128 connected to frame 124 is maintained under tension by means of a member 130 connecting the upper end of spring 128 to pad frame 12. Spring 128 resiliently presses roller 122 into engagement with the lower end of guide plate 114, and prevents the cloth from moving unless it is fed by feeding gears 118 and 120. Thus, roller 122 insures that grease cloth 24 will be held in contact with the face of pad 18.

Feeding gears 118 and 120 are rotatably mounted on the machine and are driven by a ratchet wheel 132 (Figure 1) through suitable gearing (not shown). As in the patent referred to hereinabove, at certain times during the operation of the machine, a pawl 134 is moved upwardly so that it engages and turns ratchet wheel 132 as the pad assembly 10 reciprocates. At this time ratchet wheel 132 drives the feeding gears to feed grease cloth 24 across the face of grease pad 18.

Contact member support 34 (Figure 2) has its upper end connected to a pair of brackets 136 and 138 extending outwardly from frame 12 by bolts 140. Contact members 30 and 32 are mounted on the lower ends of support 34 and include portions 30a and 32a extending longitudinally of the sides of support 34. The two conductors 26 and 28, which supply current to heating elements 20 and 22 (Figure 3), are mounted on frame 12 by a series of clamps, and the lower ends of these conductors are connected to contact members 30 and 32 by screws 142 and 144.

Brush holders 40 and 42 (Figure 5) may be of any desired construction and are mounted upon sleeve 82. The carbon brushes 36 and 38 are resiliently pressed into contact with contact members 30 and 32 by springs 146 and 148. The brushes are mounted within metal sleeves 150 and 152 to which conductors 44 and 46 (Figure 2) are soldered. A housing 154 (Figures 2, 3 and 5) is provided to protect the brushes and the electrical connections associated therewith. Thus, when the pad assembly 10 is in operation, support 34 reciprocates vertically with respect to the axes of brushes 38 and 36, which at all times remain in contact with contact members 30 and 32. Because of the connection between pad assembly 10 and sleeve 82, as described hereinabove, when pad assembly 10 turns on rod 14 (Figure 4), support 34 is always maintained in the same relationship with respect to brush holders 40 and 42 (Figure 2).

Before the machine shown in Figure 1 is placed in operation, the circuit to heating elements 20 and 22 is completed. These elements heat pad 18 (Figure 4) and thus the portion of grease cloth 24 in contact with its surface. When the machine is placed in operation, the grease on cloth 24 is evenly applied to the hat 58 (Figure 1), and the heat given off by heating elements 20 and 22 is sufficient to cause the grease to adequately penetrate. During each cycle of operation, the cloth is fed a predetermined distance across the face of pad 18 (Figure 4) by mechanism described hereinabove. Thus, an efficient and practical heated grease pad has been described which evenly applies the grease to the crown of a hat in a manner which insures adequate penetration of the body of the hat by the grease. It will thus be seen that the several objects mentioned hereinabove, as well as many others, have been successfully accomplished.

As many possible embodiments may be made of the mechanical features of the above invention, and as the art herein described might be varied in various parts, all without departing from the scope of the invention, it is to be understood that all matter hereinabove set forth or shown in the accompanying drawings is to be interpreted as illustrative and not in a limiting sense.

What is claimed is:

1. In a heated grease pad for use on a machine in which the grease pad is moved with respect to the body of a hat during the greasing operation, in combination, a supporting column, a grease pad, a heating element mounted on said grease pad, means mounting said grease pad on said column for movement with respect thereto, a pair of contact members mounted on said supporting column, and a pair of contact members mounted on said pad connected by conductors to said heating element, said pair of pad contact members being in engagement with said pair of column contact members, each pair of contact members engaging the other pair of contact members with a sliding contact as said pad moves with respect to said column.

2. In a heated grease pad for use on a machine in which the grease pad is moved with respect to the body of a hat during the greasing operation, in combination, a grease pad, a supporting column, means mounting said grease pad on said supporting column for movement with respect thereto, means for moving said grease pad with respect to said supporting column, means for moving said column to traverse said grease pad over the surface of a rotating hat crown during a greasing operation, a heating element on said pad, contact members on said pair of pad contact members being in engagement with said pair of column contact members, said pad connected by conductors to said heating element, and a pair of contact members on said supporting column, said pad contact members moving longitudinally between said column contact members during operation of the machine.

3. In a heated grease pad for use on a machine in which the grease pad is moved with respect to the body of a hat during the greasing operation, in combination, a supporting column, a grease pad mounted on said column for longitudinal movement with respect thereto, means for moving said pad with respect to said column during a greasing operation, a heating element on said pad, a pair of contact members on said pad connected to said heating element and extending longitudinally thereof, and a pair of contact members on said column connected to a source of current, said pair of pad contact members being in engagement with said pair of column contact members, said column contact members engaging said pad contact members and remaining in engagement with them as said pad contact members move with respect to said column contact members.

4. In a heated grease pad for use on a machine in which the grease pad is moved with respect to the body of a hat during the greasing operation, in combination, a supporting column, a grease pad mounted on said column for movement with respect thereto, means for moving said pad with respect to said column during a greasing operation, a heating element on said pad, a pair of rigid contact members on said pad connected to said heating element, a pair of brushes on said supporting column engaging said contact mem-

bers, means connecting said pair of brushes to a source of current, said pair of brushes being in engagement with said pair of contact members, said pair of brushes remaining in contact with said contact members as said pad reciprocates with respect to said column.

5. In a heated grease pad for use on a machine in which the grease pad is reciprocated with respect to the body of a hat during the greasing operation, in combination, a supporting column, a heated grease pad mounted on said column, means for reciprocating said heated grease pad longitudinally with respect to said column, means mounting said pad for rotation with respect to the longitudinal axis of said column, a heating element mounted on said pad, a pair of contact members mounted on said pad, means electrically connecting said contact members to said heating element, a sleeve rotatably mounted on said column, a pair of contact members mounted on said sleeve, said pair of pad contact members being in engagement with said pair of contact members on said sleeve means connecting said sleeve contact members to a source of current, and means connecting said pad and said sleeve to cause said sleeve to turn as said pad turns, each pair of contact members engaging the other pair of contact members with a sliding contact and maintaining contact as said pad reciprocates.

6. In a heated grease pad for use on a machine in which the grease pad is reciprocated with respect to the body of a hat during the greasing operation, in combination, a supporting column, a grease pad mounted on said column, means for reciprocating said pad with respect to said column, a heating element mounted on said pad, a pair of contact members mounted on said pad electrically connected to said heating element, a pair of contact members mounted on said column, the contact members on said pad reciprocating with respect to said column contact members, said pair of pad contact members being in engagement with said pair of column contact members, said pad contact members slidably engaging said column contact members as said pad reciprocates with respect to said column.

7. In a heated grease pad for use on a machine in which the grease pad is reciprocated with respect to the body of a hat during the greasing operation, in combination, a supporting column, a pad mounted on said column for longitudinal movement with respect thereto, means for driving said pad with a reciprocating action with respect to said column during a greasing operation, a heating element on said pad, a pair of contact members on said pad connected to said heating element and extending longitudinally thereof, a pair of contact members on said column connected to a source of current, said column contact members being in engagement with said pad contact members and remaining in engagement with them as said pad contact members reciprocate longitudinally with respect to said column contact members, a grease cloth, and means for feeding said grease cloth across the face of said heated pad.
